UNITED STATES PATENT OFFICE.

ROY E. CHOATE, OF CEDAR RAPIDS, IOWA.

CABLE-TAKE-UP GRIP.

1,425,077.

Specification of Letters Patent. Patented Aug. 8, 1922.

Application filed December 16, 1918. Serial No. 266,887.

To all whom it may concern:

Be it known that I, Roy E. Choate, a citizen of the United States, residing at Cedar Rapids, in the county of Linn and 5 State of Iowa, have invented certain new and useful Improvements in Cable-Take-Up Grips; and I do hereby declare the following to be a full, clear, and exact description of the invention, such as will enable others skilled in the art to which it 10 pertains to make and use the same.

This invention relates to pulling devices, such as stump-pullers and the like, and the purpose of the invention is to provide a 15 simple and quickly operating take-up for the slack in cables, whereby longer or shorter hitches may be made without the necessity of reeling and unreeling the cable by turning the winch.

20 In the operation of pulling stumps, for example, it is necessary to shift from stump to stump, the distances of which from the winch will vary indefinitely. To unwind the cable to connect with a stump, or reel 25 it up at the winch, to connect with a nearer one requires considerable time and labor. The take-up herein described admits of the use of a long cable for attaching to an object at any distance within its length, and 30 in a fraction of the time required to operate the winch.

In the accompanying drawing, forming 35 a part of this specification, Fig. 1 is a side view in perspective, showing the improved take-up as in use. Fig. 2 is a top view of the same detached. Fig. 3 is a bottom view of the same. Fig. 4 is a section of the same in the line 4—4 of Fig. 2.

In the drawing, the numeral 1 denotes the 40 pulling winch having a cable drum 2 and power sweep 3. The winch is connected to some stable anchorage, as a stump 4, by a cable 5. On the drum is wound the pulling cable 6, which may be as long as desired. The pull of this cable is applied to 45 the object to be pulled, a stump 7, for example, by an auxiliary cable 8, through the medium of the take-up which will now be described.

To the cable 8 is secured a strong casting, preferably of steel by its cable-end 50 socket 9, in which the cable is leaded in a familiar way. The casting has a flat top 10, slotted at 11, and is provided with an opening at 12. At the opposite end is an upstanding jaw 10', whose inner face is

curved as shown. Lateral to this jaw is a hook 13 to receive the cable 6 in direct alignment with the cable 8, as seen from above, and after a turn thereof has been 60 made about the gripping disk, to be described presently. Depending flanges 14 serve to support the casting on the ground, and give space for the parts of the disk that connect with the casting. At one side 65 is formed a handle 15 by which the take-up is carried.

On the flat top of the casting is mounted a circular disk 16, provided with a circumferential groove 17 to receive the cable 70 6, a gap in the upper flange of the disk being made at 18 to permit the "dead-end" portion of the cable to overlie the part that passes through the hook and on to the winch, as plainly shown in Fig. 2. At the 75 side of the disk which adjoins the jaw a depending lug 19 passes through the slot 11, and is provided with a retaining cotter-pin 20. At the opposite side of the disk is a strong hook 21 which enters the opening 80 12, and holds the flat lower face of the disk in contact with the top of the casting, while allowing for a limited movement of the disk on said casting.

The operation of the device will be 85 readily seen. When the cable 6 is slack its own elasticity forces the disk to open position with respect to the jaw of the casting, which may be designated as the fixed member. The operator may then easily 90 detach the cable, and connect the cable 8 with another stump. Whether nearer or farther away, he has only to throw a loop of the cable 6 around the disk, and hold the loose end of the cable lightly while the 95 winch takes up the slack. In so doing the disk is drawn bodily toward the jaw, a segment of the cable being gripped between them, the grip of the parts increasing as the strain increases.

The construction of the take-up is such 100 that the cables 6 and 8 are brought to exact alignment under stress, the take-up tipping a little when such stress is applied. Any tendency of the take-up to twist is prevented by the guide-hook over the pulling cable. It is to be noted that the movement of the grooved disk is directly radial, insuring an equal distribution of pressure 105 over the whole segment of cable gripped 110 between it and the correspondingly curved face of the opposing jaw. This segment,

- as will be seen, is a part of the "dead end" of the cable, and between it and the active, pulling part of the cable is a nearly complete turn of cable fitting snugly in a groove, the friction of which corresponds to the friction of coils of rope snubbed around a post, and greatly relieves what would otherwise be a very great longitudinal strain of the cable at the place gripped.
- 10 This relieves the cables of any excessive squeezing or abrading action under the very great strains to which it is subjected.

Having thus described my invention, I claim:

- 15 1. A cable take-up, comprising a fixed member permanently attached to a cable, and having at one side an upstanding jaw with a guide-hook lateral thereto and substantially in line with the attached cable,
- 20 a circular, grooved disk mounted slidably on the fixed member, to receive a turn of cable, and hold a segment thereof against said jaw by the pull of the encircling cable and guides co-operating to prevent the turning of one member on the other.
- 25 2. A cable take-up, comprising in combination a fixed member with a section of cable permanently attached thereto, and having at one side an inwardly curved, up-
- 30 standing jaw, with a guide-hook lateral thereto to hold an auxiliary cable in line with the attached cable, a circular, peripherally grooved disk mounted slidably on the fixed member toward and from said jaw, a
- 35 part of one of its flanges being cut away to

allow for an offset in the encircling cable, substantially as described, and guides co-operating to prevent the turning of one member on the other.

3. A cable take-up, comprising a fixed 40 member with a section of cable attached thereto, and having an upstanding jaw to engage a segment of cable and a cable-guide lateral thereto, the top of said member being slotted and its end open, substantially 45 as described, and a circular, peripherally grooved disk having a depending lug to pass through said slot, and a hook entering said end opening, and whereby the disk is held to slide in a direction perpendicular to said 50 jaw, and means connecting with said lug to hold the parts together.

4. A cable take-up, comprising the fixed member having an inwardly concaved jaw, a lateral cable-guide, a carrying handle, a 55 slot in its top and an end opening, and a co-operating circular disk peripherally grooved to receive a turn of cable, and provided with a depending lug to slide in said slot, retaining means therefor, and an end 60 hook entering said end opening, whereby the disk is made slidabile in a direction perpendicular to said jaw.

In testimony whereof I affix my signature in presence of two witnesses.

ROY E. CHOATE.
